Beaver Falls, Pa. 15010

Continuation of application Ser. No. 388,456, Aug. 10,
1964. This application Oct. 17, 1966, Ser. No. 587,340
U.S. Cl. 287—52.05
Int. Cl. F16d 1/06

3 Claims

This invention relates to means for adapting certain hexagonal types of machine keys to the rectangular keyspaces of "standard" machine keys, so that a rigid connection is effected.

This application is a continuation of my application Ser. No. 388,456 filed Aug. 10, 1964, now abandoned.

Objects of the invention are to provide, in keyspaces of rectangular shape, for vertical and lateral impacting pressures automatically and proportionally adjusted as between upper and lower keyways; for the use of shimming at one or more keyway faces with rotatably distributed pressuring effect at all faces; and generally, by residual impaction at all working faces, to prevent all relative movement of the faces and thus to obtain durability to the keyage under hard reversing duty.

Reference is here made to my copending applications, Ser. No. 294,369, filed July 11, 1963 and now Patent No. 3,362,734, and Ser. No. 325,808 filed Nov. 19, 1963 and now abandoned, for more detailed descriptions of the hexagonal key types with use of which the present application is concerned. The keys are referred to herein respectively as the expanding hexagon and the wedge hexagon types. The same reference is made for a fuller explanation of an inherent and well-known difficulty encountered in the operation of the rectangular sectioned standard machine keys currently in general use. In summary that difficulty is that, under heavy pulsative or reverse impact duty, the rectangular keys all begin to loosen, that is begin slowly to fail, with the first few hard and sharp transverse loadings; this even though the maximum shear force applied is but a minor fraction of the actual shear strength of the key. The two hexagonal keys referred to, with their triple-wedging principle, to tactile wedges engaging the keyed members and a longitudinal wedging of either horizontal or vertical action for the seating of the tactile wedges, cannot be made to fit or work with direct bearing in the existing standard keyways; this because of the parallel sidewalls and the consequent compartmentation of lateral spreading forces of the key in each keyway. The present invention, at the cost of certain small auxiliary parts, makes the hexagonal keys effectively applicable in existing machines without the relatively very large expense and delay which would be entailed by disassembly and the cutting of new keyways or the substitution of new keyed members having appropriate wedgeform keyways.

In the accompanying drawings, for clarity, longitudinal slope angles are exaggerated, shim thicknesses are more substantial than would be normally required, the members are varied slightly in length and the keys are shown as gripping at positions other than their mean or nominal point of tightening range. As to reference characters, capital letters are used, with arrows to indicate physically separable members and numbers are used to indicate areas, lines and reference points.

2

FIG. 1 is a side elevation of a representative form of wedge hexagon key with adapter elements in place and showing in section adjacent portions of a hub and shaft keywayed for a square tapered standard key. Portions of the near side upper and lower adapters are broken away at the front or right hand end of the key.

FIG. 2 is a plan view of the structure of FIG. 1 but omitting the hub and with a portion of one upper adapter broken away at the right hand end.

FIG. 3 is an enlarged cross section on line 3—3 of FIG. 1, with a portion of the key broken away at the right hand side to show the adapter pieces more clearly.

FIG. 4 is a bottom view of the near-side upper adapter of FIG. 1.

FIG. 5 is a bottom view of the near-side lower adapter of FIG. 1.

FIG. 6 is a side elevation of a second form, a straight, split, expanding hexagon key with adapter elements in place and, in section, adjacent portions of hub and shaft keywayed as for a straight square standard key. Portions of the near side upper and lower adapters are broken away at the right end.

FIG. 7 is a plan view of the structure of FIG. 6 but omitting the hub, and with a portion of one upper adapter broken away at the right end.

FIG. 8 is an enlarged view of the structure of FIG. 6, partially in section on line 8—8. A portion of the key itself is broken away at the right.

FIG. 9 is a transverse view of a third form, taken at a position corresponding to that of FIG. 8. A portion of the key is broken away at the right. (Longitudinal views of this construction are omitted as being the same as FIGS. 6 and 7 except for the addition of the lateral filler plates to be described.)

FIG. 10 is a transverse view of a fourth form, likewise taken at the end of the hub, the view corresponding to FIG. 3. A portion of the key is broken away at the right. (Here also longitudinal views are omitted as being similar to FIGS. 1 and 2 except for the addition of certain shims to be described.)

Now referring more particularly to the drawings, in the first construction, FIGS. 1—5, A is a wedge hexagon key, B and C are upper or hub keyway angular fillers, herein called adapters, and D and E are lower or shaft keyway adapters. F and G are respectively adjacent portions of the hub and shaft in which a standard square tapered key-space is formed. 1—1 is the median line or longitudinal axis of the keyage, 2 (FIG. 3) is the arc of the shaft surface and hub bore, 2a is a horizontal line through the lip points of the keyways, and 3, 4 are the inner edges of the upper adapters B, C, which edges are parallel as are the corresponding edges of the lower adapters D, E. 5 (FIG. 1) is the sloping top surface of the key A, and 6 is the floor of the upper keyway, these being in parallel planes, 7, 8 and 7a, 8a are respectively the vertical outer faces and top faces of the upper adapters B, C, in pressured contact with the sidewalls and floor of the upper keyway. Points 9, 10 (circled, FIG. 3) indicate the lip lines of both keyways. 7b, 8b are the triangular bottom faces of the upper adapters, located in or slightly above 2a, the plane of the lip lines 9, 10, 11, 12 (FIGS. 1, 2) are the lines of intersection of upper and lower flanks of the key. 13, 14 are respectively the parallel planes of the shaft keyway floor and the bottom surface of the key.

15, 16 and 15a, 16a are respectively the vertical outer surfaces and bottom faces of the lower adapters, in pressured contact with the side-walls and floor of the lower keyway. The rectangular axes 1 and 2a (FIG. 3) divide the keyage into four quarter-areas or quadrants for convenience in referring to adapter locations. Similar axial division is considered to apply also to the other three forms, FIGS. 8, 9 and 10. Where the two keyways differ in width, as in FIG. 10, the horizontal axis is considered to be located in the plane of the lip lines of the wider keyway.

In the second construction, FIGS. 6, 7, 8, H and J are the halves of an expanding hexagon key in set position in a square straight standard keyway. K, L are the upper adapters and M, N the lower, all four of which may be alike. P, Q are respectively adjacent portions of hub and shaft. 31-31 is the median line or longitudinal axis of the keyage and 31a (FIG. 7) the pitch plane of the inter-fitting serrations of the halves. 32 (FIG. 8) is the arc of the shaft and bore surfaces. Points 33, 34 (circled, FIG. 8) represent the lip lines of both upper and lower keyways. 33a (FIG. 6) is the line of intersection of the near-side upper and lower flank planes and nominally coincides with the keyway lip line. (It may rise or fall slightly as the key finds its pressure balance in the specific keyage.) 35, 36 are respectively the parallel top surface of the key and the upper keyway floor. 37, 38 and 41, 42 are the outer vertical faces respectively of the upper and lower adapters; 37a, 38a and 41a, 42a being the respective horizontal floor-contacting faces; all being in pressured contact with the respective keyway surfaces. 39, 40 are respectively the parallel but non-contacting bottom key surface and the shaft keyway floor.

In the third construction, FIG. 9, R, S are the halves of an expanding hexagon key, T, U and V, W are lateral fillers respectively in upper and lower straight flat standard keyways and X, Y are respectively adjacent portions of the hub and shaft. 51-51 is the median plane or axis of the keyage, 52 is the arc of shaft surface and hub bore, 53, 56 are respectively the upper and lower keyway floors, and 54, 55 and 57, 58 are the outer faces of the four lateral fillers. The key and triangular adapters are of the same type as those of FIGS. 6, 7, 8, in similarly set position, adjusted in size to suit the construction and so need no particular description.

In the fourth construction, FIG. 10, Z is a wedge hexagon key. AA is a floor shim in the upper keyway. AB, AC are lateral shims in the lower keyway and AD a floor shim, likewise in the lower keyway. AE, AF are adjacent portions respectively of hub and shaft. 61-61 is the median plane or axis of the keyage and 62 is the arc of shaft and bore. In contact with the upper keyway floor, the sloping top surface of the floor shim AA is clearly shown. 65, 66 are the outer vertical faces of the upper adapters. 67 is the lower face of floor shim AD, in contact with the shaft keyway floor. 68, 69 are the outer faces of the lateral shims, in contact with the keyway side walls. The key and triangular adapters are exactly like those of FIGS. 1-6, are in similarly set position and so need no particular description.

In the FIG. 10 construction, illustrating a combination of both vertical and horizontal shims, the particular keyway condition assumed to be met is that of a hub keyway of excessive depth and a shaft keyway which has been refinished in maintenance to oversize dimensions in both width and depth, thus requiring, for repair in the rectangular key system, an oversize key especially offset or shoulder-ground to fit the mismatched keyways. Conversion to a standardized hexagonal key, with its regular complement of standardized adapters and using staple shim stock for the straight dimensional make-up, offers, in addition to the system advantage of full impaction, the economy of avoiding special machining of the key. The versatility here illustrated is derived from the same inherent qualities of the pressured hexagonal keys as the

direct face shimming of those keys, namely the angular incidence of pressure faces; permitting insertion, adjustment and solid equalized residual impaction, and thus the retention and preservation, of the make-up pieces.

As to installation, in the first and fourth constructions the key and supplementary pieces are inserted and arranged manually a short distance in rear of the desired final gripping position, the pieces being somewhat in advance of the key itself; and the key is then hammer-driven into place. In the second and third constructions, FIGS. 6-8 and 9, the key, in contracted lateral adjustment, is inserted, with its supplementary pieces, and placed manually at the approximate desired final position, allowance being made for the appropriate opposite driving movements of the halves and for the normally lesser movements of the contacting auxiliary pieces. Two precautions are of sufficient practical importance in each installation of either key type to justify statement: (1) Before driving or setting of key, see that the specific keyways are centrally co-aligned vertically, for true bearing at each face. Adapters may be filed appropriately if necessary for correction of bearing. (2) After setting, see that complete floor clearance has been obtained at top and bottom faces of the key.

In actual operating principle, after installation, the two types of keys are substantially the same. In both cases solid residual pressures, developed at the four working faces by the setting of the key, maintain all contacts with sufficient reserve pressure to prevent relative movement of surfaces regardless of frequency of pulsations or direction reversals of the operating load imposed by the displacement forces in the keyed members.

In all of these adaptive constructions the radial and tangential components of the key face forces are necessarily separated in their application to the rectangular keyway, the radial being exerted exclusively upon the floors and the tangential exclusively upon the walls. But the combined origin of the diverse forces precludes interference between their separate functions, axial gripping and rotative fixing of the members, just as in the hexagonal type's own convergent-walled keyways. Here the radial component force impacts and retains the floor shims and the tangential component force impacts and retains the wall shims. A total of eight keyway areas are thus proportionately pressured; in FIG. 8 for example, those areas contacted by surfaces 37a, 38a, 37, 38, 41, 42, 41a, 42a, as against the four areas in the key itself; and there can be no pressure change at any one or between any opposing pair of areas without corresponding change at all eight.

It will be understood that all of the filler and shim uses of FIGS. 9 and 10 may be applied with either type of the hexagonal keys; that is, that the lateral fillers of FIG. 9 for size substitution may be applied as well with the wedge hexagon key of the first and fourth constructions, and that the recourse shimmings of FIG. 10 may be applied with the expanding hexagon key of the second and third constructions. I desire it to be understood that I may practice the invention with all such variations of construction as may fall within the spirit of the invention and the scope of the appended claims such as: the proportions and supplemental angle of the triangular adapters, the use of lateral shims of unequal thickness either for convenience of installation or for alternation of index of the keyed members, and means for fastening the auxiliary pieces in place.

I claim:

1. In combination, two machine members having mutually contacting surfaces, two co-operative channel-shaped keyways formed in said surfaces, each keyway having two sidewalls in parallel planes; a hexagonal and laterally expandable key having two convergent pressure faces extending into each keyway; and two triangular adapter pieces within the confines of each keyway each having one face parallel with one of said key pressure

faces and one face parallel with one of said keyway walls, whereby expansive force of said key may be transmitted and ratably maintained between said key and all four of the walls of said keyways.

2. In combination, two machine members having mutually contacting surfaces; two co-operative channel-shaped keyways formed in said surfaces, each keyway having two sidewalls in parallel planes, a hexagonal and vertically wedging key having two convergent pressure faces extending into each keyway; and two substantially triangular adapter pieces within the confines of each keyway each having one face longitudinally parallel with one of said key pressure faces and one face longitudinally parallel with one of said keyway walls, whereby wedging force of said key may be transmitted and ratably maintained between said key and all four walls of said keyways.

3. The invention defined in claim 2, wherein one of said keyways has its floor extending at an acute angle to the floor of the other keyway.
